2 Claims. (Cl. 112—158)

ABSTRACT OF THE DISCLOSURE

A sewing machine capable of zig-zag movements having a vertically reciprocating hollow tubular needle bar with a special oscillatory actuating means therewithin which cause two needles pivotally attached to the needle bar, and each having a flat tang of a thickness equal to the diameter of the needle shank, to oscillate in a horizontal plane independently toward and away from each other to produce symmetrical left and right patterns of stitches.

This invention relates to sewing machines and more particularly to a new double needle action, needle-bar device in a fancy-stitching sewing machine.

Throughout the following disclosure and appended claims, all stated directions are those as viewed from the sewing machine operator's position.

Briefly stated, the present invention provides a double needle action, needle-bar device positioned at and partly enclosed within the left-hand end the machine arm of a fancy-stitching sewing machine and comprising: a tubular needle bar driven in vertical reciprocating motion slidingly in upper and lower guide holes in the machine are by a mechanism driven in turn by the main driving shaft of the machine, said needle bar being provided with a horizontally disposed flat plate fixed to the lower end thereof and extending rearwardly; left and right needle holders in parallel, side-by-side disposition, respectively pivoted at their rear ends for oscillatory motion in the horizontal plane by pins on the lower rear surface of said flat plate and holding respective sewing needles; and a thin shaft inserted in the tubular needle bar and actuated by the zig-zag sewing mechanism of the machine, said thin shaft having a cam fixed to its lower end, which cam is in constant contact with said left and right needle holders and operates to actuate said needle holders in oscillatory motion about their pivots, whereby the needles are caused to sew a symmetrical pattern in accordance with the actuation by the cam.

The present invention furthermore provides a novel sewing machine needle suitable for the needle bar device of the invention, which needle has a flattened tang of a thickness equal to the diameter of the needle shank.

The nature, principle, and details of the invention will be more fully apparent by reference to the following description with respect to a preferred embodiment of the invention, when taken in conjunction with the accompanying drawings throughout which like parts are designated by like reference characters, and in which:

FIG. 1 is an end elevational view, with parts cut away, showing the embodiment of the needle-bar device according to the invention;

FIG. 2 is a partial elevational view from the operator's position, partly in section and with parts cut away, of the device shown in FIG. 1;

FIG. 3 is a plan view, with a part cut away, showing certain parts of the needle bar device;

2

FIG. 4 is a combination of an elevational view and a perspective view showing the needle bar assembly;

FIG. 5 is a sectional view taken along the plane indicated by line V—V in FIG. 4;

5 FIG. 6 is a perspective view showing the relative positions of a needle holder and the control cam;

FIG. 7 is a diagram showing examples of stitching patterns which can be readily sewn by the use of the device of the invention;

10 FIG. 8 is an elevational view showing a needle suitable for use in the device of the invention; and

FIG. 9 is a top plan view of the needle shown in FIG. 8.

Referring to the drawings, the needle-bar device embodying the invention is disposed at the left end of the

15 arm of a sewing machine and is provided with a tubular needle bar 1 having an axial through hole in which a thin shaft 2' is slidably inserted. At the lower end of the needle bar 1, there is fixed a flat plate 1' extending toward the rear of the sewing machine. On the bottom surface of this flat plate 1', there are pivotally supported by pins 1" left and right needle chucks or holders 11', 11, 11" each having an inverted L shape and having a smooth upper surface. These holders are so supported that each holder can be swung open individually about the pin 1"

25 as a pivot.

The thin shaft 2' inserted in the hollow interior of the needle bar 1 has a cam 2 fixed to its lower end. The cam 2 is disposed between the left and right needle holders of

30 inverted L shape and is in contact with contact surface 11''' of each holder, whereby needles 13 and 13' held at the front ends of the needle holders are respectively caused to swing horizontally to the left and right by the rotational displacement of the cam 2.

35 Leaf springs 20, 20 each anchored at one end to the flat plate 1' by a screw 22, impart inward forces on the outer side surfaces of the holder members 11', 11' tending to swing the members 11', 11' toward each other, whereby the needles 13 and 13' held by the needle holders are urged toward each other.

40 Each needle holder is provided with a groove partly formed in the member 11 and partly in the clamp member 11'', the flat tang F of a needle being fitted into this groove and clamped in place at its rounded side edges 13'', 13'' by a clamping force exerted by a clamp screw 12 by way of the clamp member 11'' as best shown in FIGS. 5 and 6.

45 As shown in FIGS. 8 and 9, each needle for use in the device of the invention is a round needle provided at its securing end with a flattened tang F which has a thickness equal to the diameter of the needle shank 13. Therefore, when the left and right needles are placed in contact with each other, the two needle shanks can be positioned very close together as shown in FIG. 4, and the space between the left and right needles can be reduced to a minimum as indicated in FIG. 7. The reduction of this space, that is, the part left unstitched, to a minimum not only is convenient but contributes to the production of esthetically pleasant stitching patterns.

50 60 Above the contact surface 11''' of each needle holder, there is formed a flange 23 which rests on the upper surface of the cam 2, whereby wobbling during operation of the needle holder 11 which would otherwise be in an unstable state of being supported at only its pivot pin 1'' is prevented.

65 The tubular needle bar 1 is provided at its upper part with a stop ring 4 fixed by a knock pin 4' to the aforementioned thin shaft 2' inserted in the needle bar 1, the combination of the cam 2 at the lower end, the stop ring 4, and the tubular needle bar being so assembled in a state of no end play.

70 Approximately 35 mm. of the upper end 2'' of the thin

shaft 2' is formed with a square cross section. This square part 2" of the shaft is slidably fitted in a central square hole in a rotating bearing 6 engaged within a tapped hole in the upper end of a needle-bar guide tube 5 provided at the left end of the sewing machine arm. The square shaft part 2" slides up and down within the square hole as it moves together with the ascending and descending needle bar 1.

The square hole, rotating bearing 6 is provided at its upper end with an arm 6', to which the displacement of a connecting rod 7 caused by a mechanism (not shown) for producing needle oscillation for zig-zag sewing is transmitted, whereby the bearing 6 undergoes reciprocating rotational movement.

When a sewing machine provided with the above described needle bar device is operated, the needle bar 1 undergoes vertical reciprocating motion, and the square-hole rotating bearing 6 varies its twisting angle when a variation is produced in the amplitude of the movement of the connecting rod 7 due to the cam (not shown) of the zig-zag producing mechanism (also not shown). Accordingly, the shaft 2", 2' fitted in the square hole undergoes twisting motion, whereby the cam 2 at the lower end of the shaft 2' causes the needle holders 11, 11 in contact therewith to undergo left and right, opening and closing, oscillatory motion in a synchronous manner as indicated by arrows in the drawings. As a result, the two needles 13 and 13' held also are caused to oscillate left and right, thereby to sew stitch patterns, as shown in FIG. 7, which are symmetrical left and right.

By using threads of two colors for the left and right symmetrical patterns, uniquely beautiful patterns can be readily stitched, whereby the versatility of zig-zag sewing machines can be further broadened.

It should be understood, of course, that the foregoing disclosure relates to only a preferred embodiment of the invention and that it is intended to cover all changes and modifications of the example of the invention herein chosen for the purposes of the disclosure, which do not constitute departures from the spirit and scope of the invention as set forth in the appended claims.

What I claim is:

1. In a sewing machine of the type having a main driving mechanism and a mechanism for producing zig-zag movements, a double-needle action needle-bar device comprising a tubular needle bar driven in vertical reciprocating motion by the main driving mechanism; needle holding means comprising a horizontally disposed flat plate fixed at the lower end of the needle-bar device and extending rearwardly, moving vertically together with the needle bar, and left and right needle holders in parallel and symmetrical disposition adapted to hold two needles constantly in vertical alignment parallel to said motion of the needle bar but with freedom to undergo motion horizontal and transverse to the principal sewing direction of the machine; each said needle holder being pivoted at its rear end by a pin supported by the rear end of the flat plate so as to be free to undergo horizontal oscillatory motion toward and away from the other needle holder; said needle holders vertically holding respective needles; a drive transmission comprising a thin shaft inserted within said tubular needle bar and provided, at its lower end, with a cam to cause said oscillatory motion of each needle holder; and drive means to drive the thin shaft in accordance with said zig-zag movements.
- 10 2. A sewing machine needle for use in the device of claim 1, each of said needles having a flat tang of a thickness equal to the diameter of the shank or working part of the needles.
